Primary Examiner — Marie D. Fast Horse

(57) **CLAIM**

The ornamental design for wooden phone docking station, as shown and described.

DESCRIPTION

FIG. 1 is a front, right side perspective view of wooden phone docking station, showing my new design;

FIG. 2 is a rear, left side perspective view of the wooden phone docking station;

FIG. 3 is a front elevational view thereof;

FIG. 4 is a rear devotional view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show portions of the wooden phone docking station that form no part of the claimed design.

1 Claim, 8 Drawing Sheets
